Primary Examiner — Llorellys Martinez(57) **CLAIM**

The ornamental design for a bracelet, as shown and described.

DESCRIPTION

FIG. 1 is a top-front perspective view of a bracelet showing my new design;

FIG. 2 is a top-rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right elevation view thereof; and,

FIG. 8 is a left elevation view thereof.

The broken lines showing text indicia in FIGS. 1, 3, and 5-8 represent environmental structure only and form no part of the claimed design.
